(57) **CLAIM**

The ornamental design for a gun slide as shown and described.

DESCRIPTION

FIG. 1 is a perspective front, top-left view of a gun slide, showing my new design;

FIG. 2 is a perspective back, top-left view of the gun slide design of FIG. 1;

FIG. 3 is a perspective front, top-right view of the gun slide design of FIG. 1;

FIG. 4 is a perspective back, top-right view of the gun slide design of FIG. 1;

FIG. 5 is a perspective front, bottom-left view of the gun slide design of FIG. 1;

FIG. 6 is a perspective back, bottom-left view of the gun slide design of FIG. 1;

FIG. 7 is a perspective front, bottom-right view of the gun slide design of FIG. 1;

FIG. 8 is a perspective back, bottom-right view of the gun slide design of FIG. 1;

FIG. 9 is left side view of the gun slide design of FIG. 1;

FIG. 10 is a right side view of the gun slide design of FIG. 1;

FIG. 11 is a top side view of the gun slide design of FIG. 1;

FIG. 12 is a bottom side view of the gun slide design of FIG. 1;

FIG. 13 is a back view of the gun slide design of FIG. 1;

FIG. 14 is a front view of the gun slide design of FIG. 1;

FIG. 15 is a cross-sectional view of the gun slide design of FIG. 1 down the vertical left portion as shown in FIG. 11 showing the inside of the right portion of the gun slide;

FIG. 16 is a perspective cross-sectional front, top-right view of the gun slide design of FIG. 1 as shown in FIG. 15;

FIG. 17 is a perspective top, left-front cross-sectional view of the gun slide design of FIG. 1 down the vertical center as shown in FIG. 11 showing the inside of the left half of the gun slide; and,

(Continued)

FIG. 18 is a left-side view of the gun slide design of FIG. 1 as shown in FIG. 17.
